UNITED STATES PATENT OFFICE

FRANK E. STOVER, OF LURAY, VIRGINIA, ASSIGNOR OF ONE-THIRD TO WHITNEY E. BUNDY AND ONE-THIRD TO FRANK G. DAVIS, BOTH OF SPRINGFIELD, OHIO

INCUBATOR

Application filed July 23, 1926. Serial No. 124,528.

My invention relates to incubators.

It is an object of my invention to provide an incubator heated by natural draft in which the passage of air over individual trays can be controlled manually or automatically depending upon the heat in the area surrounding that particular tray.

It is a further object of my invention to provide means for circulating air by natural draft and to control that circulation as well as control the inlet and exit of fresh and foul air.

It is a further object of the invention to provide a circulating means by which the hot air will pass over a cooling radiator, such radiator being preferably composed of a plurality of passageways through which external air may pass to cool the internal air in a predetermined part of the cabinet.

It is my object to provide a re-circulating incubator and one which may automatically withdraw from circulation a portion of the air under the induction of the heater draft.

It is my object to provide an automatic vent that can be set for constant changing of the air with an automatic arrangement, so that in case of overheating an extra quantity of air will pass through the incubator eliminating the danger of overheating, such overheating being taken care of at two points, one by an automatic ventilator controlled by the temperature at the top of the cabinet and by a temperature control connected to the exhaust of the heater, so that air will be drawn up the heater flue by the exhaust heat of the heat generator.

It is a further object to control the heat generator as to the passage of air therethrough according to the temperature in the cabinet.

It is my object to provide a cabinet incubator in which there are sub-trays acting as baffles between the egg trays for directing the air through the desired channels. These baffles also provide dust and dirt collectors

to prevent material from the eggs above falling on the eggs below.

It is my object to provide means for directing the air in such a manner as to envelop the trays, and, at the same time, provide for a slow movement of air through the eggs.

It is my object to provide an automatic fresh air inlet at the top of the air duct drawing the cool air down with the heated air thereby increasing circulation. This circulation gets its additional impulse from the flue draft stimulated by the heat thrown off by the heat generator, thus forcing out the foul air.

By the arrangement of the independent tray units it is possible to pass the air through the units without passing the air from one unit to the other, which obviates any necessity of taking care of any heat which may be discharged to the air by the more highly heated eggs.

It is my object to conduct the combined heavy carbon dioxide and the remainder of the lighter air to the bottom of the cabinet where the heavier carbon dioxide can be extracted through my exit passageway under induced draft while the lighter air free from carbon dioxide will rise to the trays again, thus making an automatic machine for eliminating carbon dioxide from the machine.

Referring to the drawings:

Figure 1 is a view taken on a vertical section through the incubator on the line 1—1 of Figure 4;

Figure 2 is a section on the line 2—2 of Figure 1 looking in the direction of the arrows;

Figure 3 is a section on the line 3—3 of Figure 1 looking in the direction of the arrows;

Figure 4 is a plan view partially broken away;

Figure 5 is a section through the top of

the cabinet, top of one of the cool air circulating pipes and the damper therefor;

Figure 6 is a side elevation showing the arrangement of doors;

5 Figure 7 is an enlarged section similar to Figure 1 showing the tray arrangement.

Referring to the drawings in detail, 1 is the bottom of a cabinet having a rear wall 2, a front wall 3 and a top wall 4. 5 designates one side wall while 6 designates the other side wall in which are located a plurality of doors 7 having hinges 8 and latches 9. The cabinet is mounted upon legs 10 a suitable distance above the supporting floor.

15 15 A heater is provided which has a dual purpose of supplying heat to the cabinet and of causing a circulation and exhaust of the air in the cabinet. This heater consists of a casing 11 mounted on legs 12. In this casing is mounted a heater 13. Above the heater is a flue wall 14 having a conical vent 15 which embodies in it a similar spaced conical vent 15 which embodies in it a similar spaced conical vent 16 forming the inside 20 wall of the water container 17.

This vent 16 is open at the bottom at 18 for the circulation of air which is drawn in between the walls of the water container 17 and of the flue 14.

30 30 The air thus drawn in is discharged out the top of the vent 16 which is controlled by the damper 18a and then passes out the chimney 19 of the heater.

The water chamber 17 communicates with 35 a plurality of radiator pipes 20 which are located in the bottom of the cabinet.

The bottom of the heater 11 is provided with a flue or inlet pipe 21. This inlet pipe has an automatic suction damper 22 pivoted 40 at 23 adapted to open out. If for any reason the pressure in pipe 21 becomes excessive the valve 22 will swing out to permit the escape of air from pipe 21. A similar damper is shown in the stack 19 designated 24 pivoted 45 at 25 but adapted to open in. The suction in the pipe line 21 or 19 will determine whether the dampers open against the influence of the weight 25a.

50 50 The damper 18a is controlled by the thermostat 26 which is located within the cabinet in the path of the rising hot air; when the heat becomes too great the thermostat expands operating the links 27 and 28, lever 29, link 30 and link 31 to open the damper 18a, thus permitting the air to pass through the vent 16, out through the chimney 19 instead of passing down and up around the water container 17. By this means the air passes directly through the vent 16 into the chimney 60 60 without any further heating of the water in the chamber 17. If the draft in 19 becomes excessive the damper 24 will open to admit outside air and thereby reduce the draft around the heater.

65 65 Returning to the cabinet, it will be ob-

served that there is a transverse partition 33 across a portion of the cabinet terminating beneath the right hand edge of the lowermost tray leaving a space 34 therebetween for the passage of hot air upwardly through the 70 trays. A vertical partition 35 is located in the cabinet spaced from the wall 3 adjoining the transverse partition 33 and extending down to a point above the floor of the cabinet leaving a space 36 for the circulation of air 75 therethrough. It is also spaced from the top of the cabinet leaving a circulation space designated 37.

This partition 35 forms a vertical passageway 80 designated 38 through which the hot air discharged at the top can pass downwardly and thence into the cabinet again through the passageway 36 or out through the bottom exit opening 39 formed by the tubular member 40 whence it will pass into the passageway 21 to the bottom of the heater. In this passageway 38 there are a plurality of relatively small vertically-arranged pipes 41 which communicate with the air above and below the cabinet outside of the 90 cabinet so that only cool air of the outside atmosphere circulates therethrough. The tops of some of these pipes are controlled by individual dampers of any desired type, one form of which is shown in Figure 5, consisting of a housing 42 and a slide 43.

The purpose of these pipes is to permit the circulation of cool air through them in the nature of a radiator, thus cooling the air in the passageway 38 inducing its descent to 100 enhance the natural circulation in the cabinet. This circulation is still further provided for and increased by an upper transverse partition 44 which joins the upper tray at one side and is spaced at its other from the upper end of the vertical partition 35 leaving an air circulation space therebetween designated 45. In this air circulation space is a thermostat 46 mounted on a bracket 47, which thermostat is connected by a rod 48 through an adjustable screw 49 to a transverse lever 50 having a weight 51 at one end which is adjustable and a vertical damper rod 52 at the other end.

This rod 50 is suspended on a knife-edged 115 block 52 working in a knife-edged socket 53 mounted on the top of the cabinet.

The rod 52 passes down through one of the air radiator pipes 41 to a point where it is connected at 54 to a damper 55 which 120 closes the passageway 39 to prevent the exit of hot air through the passageway 21. A weight 56 is attached to this damper 55 and a set screw 57 limits its motion about its pivot 58 on the cabinet.

A third thermostat 59 is provided in the cabinet above the transverse partition 44. This thermostat is suspended on the bracket 60 and connected to the thermostat is a vertical rod 61 adjustably connected by a nut 130

62 to a transverse rod 63. This rod 63 is pivotally supported on the support 64. Its free end is connected to an exit damper 65 controlling the opening 66 while its other end is provided with a counter-balancing weight 67. Upon the heat becoming excessive in the cabinet, this damper will be opened and the hot air can make its direct exit, so that the temperature is controlled at the upper portion of the cabinet, whereas the damper 55 controls the exit of hot air in the passageway at the bottom of the cabinet when the heat is less excessive.

It will be noted that the transverse partition 44 is spaced from the wall 2 leaving a passageway 68 which is closed upon occasion manually by a damper 69 controlled by a damper rod 70.

On the other side of the top of the cabinet 20 at the top of the passageway 38 is a damper 71 pivoted at its top at 72 beneath the top 4 of the cabinet and so arranged as to swing inwardly when the suction in the passageway becomes sufficient to draw the air inwardly 25 under the damper 71, thus introducing fresh air into the chamber.

The damper 71 controls an opening which may extend the full extent of one side of the incubator, or it may be restricted to a 30 certain part of said side, as would seem advantageous.

Referring to the apparatus for supporting the eggs, 73 is an egg tray having a perforated wire bottom 74. This tray is supported 35 in guideways 75 which have horizontal ledges 76 for supporting the tray 73 and ledges 77 for supporting the next adjacent scoop 78 which has a solid bottom 79. This scoop is deeper at one end than at the other having 40 its deepest end at the entrance of the air through the passageway 80 between the scoop and the supporting ledge 76 supporting the next adjacent tray 73. Closing this opening is a damper 81 pivoted on the slide 75 at 45 82.

This damper can be controlled in one form by a rod 83 connected to the damper at one end and to an arm 84 at the other pivoted on a bracket 85 at 86, the other end of the 50 arm being connected to a thermostat 87, the thermostat being located in the space between the companion tray and the next adjacent scoop, such space being designated 88 so that the thermostat will be affected by the 55 temperature of the air after it has passed over the eggs in the particular tray which is controlled through the damper 81 so far as the passage of air thereover is concerned.

The lowermost tray is provided with a 60 damper 81a which is adapted to close against the end of the partition 33.

The principle of my invention is the assembly into units of a scoop or tray for directing the air over the eggs through the bottom thereof, the passageway thereof being

controlled by a damper for that unit and by a thermostat connected to that damper, if a thermostat is to be used.

The thermostat is connected by a bracket suspended on the next adjacent upper tray 70 and scoop support. The air passes between the bottom of the tray and the top of the scoop out through the top of the tray and outside the bottom of the next adjacent scoop. 75

Method of operation

It will be observed that the heat will rise from the heater 20 through the passageway 34 into the tray compartment 5 between each scoop and its adjacent tray through the bottom of the tray out the top thereof on the opposite side to the point of its entrance beneath the bottom of the next adjacent superimposed scoop and then pass upwardly without circulating over the other trays 80 through the next opening 45, passageway 37 down through the passageway 38 where it will be cooled by the pipes 41, through which outside air may be circulated drawing in any air through the damper 71 which may be desired, passing to the passageway 36 thence over the heater again into the new circuit. 85

If the heat on the thermostat 46 is excessive, the damper 55 will open and the air will pass out the passage 39, pipe 21 over 90 the heater and out the stack 19. Fresh air being drawn in to cool the heater or damper.

If it is desired, due to the heat, to provide automatically for the exit of air, the air will make its exit at the top through the openings 66 under the damper 65 controlled by the thermostat 59. Direct by-passing of air may be effected by the direct control of the damper 69. 100

The excessive heat in the cabinet will cause 105 a shut-down of the heater by the action of the thermostat 26.

It will be understood that I desire to comprehend within my invention such modifications as may be necessary to adapt it to varying conditions and uses. 110

Having thus fully described my invention, what I claim as new and desire to secure by Letters Patent, is:

1. In an incubator, the combination of an 115 incubator cabinet, a tray for supporting eggs having a bottom for passing air therethrough, a scoop below said tray for directing air therethrough from one end to the other, and a damper for controlling the opening between 120 the bottom of the tray and the top of the scoop through which the incoming air passes, and thermostatic means located adjacent the point of exit of air through the tray connected to said damper for controlling it. 125

2. In an incubator, the combination of a cabinet, a pair of spaced trays, a scoop associated with each of said trays therebeneath, 130 said scoop having a solid bottom and said tray having a bottom for the passage of air there-

through, means for admitting air between the top of the scoop and the bottom of the tray at one end and for preventing the escape of air at the other between said scoop and tray, whereby the air is forced to pass over the scoop through the tray and the eggs contained in the tray by the bottom of the next adjacent scoop thereover, and a damper connected to the bottom of each tray adapted to close the opening between that tray and the next adjacent scoop therebeneath, and a thermostat located between the top of the tray and the bottom of the next adjacent scoop thereabove in the path of the exit of the air and means for connecting said thermostat to the damper which controls the inlet of air making its exit over the thermostat.

3. In an incubator, a cabinet, a tray compartment, a downward circulation compartment, a radiator between the bottom of the tray compartment and the circulation compartment, a passageway between the top of the tray compartment and the circulation compartment, a fuel burner to heat said radiator exterior of the cabinet, a passageway communicating with the bottom of the incubator and the burner to provide an exit for the air from the bottom of the incubator through the burner, a baffle over the radiator to direct the heat to enter one side of the tray compartment, egg supporting trays in the tray compartment with means to pass air from one side upwardly through the trays to the other side thereof, and a second baffle over said trays having an exit opening diagonally disposed from the openings adjacent the baffle over the radiator.

4. In an incubator, a cabinet, a radiator therein, a partition therein for circulating air from the radiator through trays to the top of the cabinet, thence to the bottom of the cabinet and again through the trays in said cabinet, a passageway leading from the bottom of the cabinet, a heater in said passageway to induce the exit of air from the bottom of the cabinet, such heater also furnishing heat for the radiator in the bottom of the cabinet in the bottom thereof.

5. In an incubator, a cabinet, a radiator therein, a partition therein for circulating air from the radiator through trays to the top of the cabinet, thence to the bottom of the cabinet and again through the trays in said cabinet, a passageway leading from the bottom of the cabinet and a heater in said passageway to induce the exit of air from the bottom of the cabinet, such heater also furnishing heat for the radiator in the bottom of the cabinet, a damper in said last mentioned passageway, a thermostat in the top of the cabinet connected to said damper to control it.

6. In an incubator, a cabinet, a radiator therein, a partition therein for circulating air from the heater through trays to the top of the cabinet, thence to the bottom of the

cabinet, and again through the trays in said cabinet, a passageway leading from the bottom of the cabinet, and a heater in said passageway to induce the exit of air from the bottom of the cabinet, such heater also furnishing heat for the radiator in the bottom of the cabinet, a damper in said last mentioned passageway, a thermostat in the top of the cabinet connected to said damper to control it, a second thermostat located in said cabinet adapted to control the heater outside of the cabinet.

7. In an incubator, a cabinet, a radiator therein, a partition therein for circulating air from the heater through trays to the top of the cabinet, thence to the bottom of the cabinet and again through trays in said cabinet, a passageway leading from the bottom of the cabinet and a heater in said passageway to induce the exit of air from the bottom of the cabinet, such heater also furnishing heat for the radiator in the bottom of the cabinet, a damper in said last mentioned passageway, a thermostat in the top of the cabinet connected to said damper to control it, a second thermostat located in said cabinet adapted to control the heater outside of the cabinet, a third thermostat in said cabinet adapted to control the exit of air from the top thereof, said cabinet having an opening adapted to be controlled by said thermostat.

8. In an incubator, a cabinet, a radiator therein, a partition therein for circulating air from the radiator through trays to the top of the cabinet, thence to the bottom of the cabinet and again through the trays in said cabinet, a passageway leading from the bottom of the cabinet and a heater in said passageway to induce the exit of air from the bottom of the cabinet, such heater also furnishing heat for the radiator in the bottom of the cabinet, a damper in said last mentioned passageway, a thermostat in the top of the cabinet connected to said damper to control it, a second thermostat located in said cabinet adapted to control the heater outside of the cabinet, a third thermostat in said cabinet adapted to control the exit of air from the top thereof, said cabinet having an opening adapted to be controlled by said thermostat, and a suction damper for admitting fresh air at the top of the circulation passageway.

9. In an incubator, a cabinet, a radiator in the bottom thereof, heater means connected thereto, an exit passageway from the bottom of the cabinet passing over said heater, means for separating said cabinet into a tray compartment, and a circulation passageway communicating with the top and bottom of the compartment, a plurality of trays and scoops in said compartment with the trays between the scoops, means for controlling the passage of air between each pair of

scoops, and means for cooling the air in the circulation passageway.

10. In an incubator, a cabinet, a radiator in the bottom thereof, heating means connected thereto, an exit passageway from the bottom of the cabinet passing over said heating means, means for separating said cabinet into a tray compartment, and a circulation passageway communicating with the top and bottom of the compartment, a plurality of trays and scoops in said compartment with the trays between the scoops, means for controlling the passage of air between each pair of scoops, and means for cooling the air in the circulation passageway, said cabinet having an exit at the top thereof, means to control said exit and a thermostat in the cabinet for regulating said exit, a second thermostat adapted to control the passage of air through the passageway at the bottom of the cabinet and a third thermostat adapted to control said heating means.

11. In an incubator, a cabinet, an external heater, radiator means connected thereto located in the cabinet at the bottom thereof, a plurality of trays and scoops over said radiator, a circulation passageway communicating with the bottom of the trays to one side thereof, an exit passageway at the top of the cabinet passing under the cabinet, a stack over the heater, suction dampers in said last passageway and said stack, a thermostat control located in the cabinet controlling said external heater, a thermostat for controlling the passageway at the bottom of the cabinet connected to the heater, a thermostat for controlling the exit of air at the top of the cabinet.

12. In an incubator, a cabinet, a vertical partition to one side thereof forming a tray compartment and a circulation passageway, said partition being spaced from the top and bottom of the cabinet, a transverse partition at the bottom of the cabinet spaced above the bottom thereof and from the side walls thereof having one edge joining the vertical partition, a second transverse partition spaced from the top and sides of the cabinet near the top thereof, and trays located between the top and bottom partitions and to one side of the transverse partition, said partitions being so arranged that the air will enter at one side of the trays at the bottom and will make its exit at the other side of the trays at the top.

13. In an incubator, a cabinet, a vertical partition to one side thereof forming a tray compartment and a circulation passageway, said partition being spaced from the top and bottom of the cabinet, a transverse partition at the bottom of the cabinet spaced above the bottom thereof and from the side walls thereof having one edge joining the vertical partitions, a second transverse partition spaced from the top and sides of the

cabinet near the top thereof, and trays located between the top and bottom partitions and to one side of the transverse partition, said partitions being so arranged that the air will enter at one side of the trays at the bottom and will make its exit at the other side of the trays at the top, and a plurality of independent means for controlling the passage of air independently over each tray and therethrough.

In testimony whereof, I affix my signature.

FRANK E. STOVER.
